US0D1100520S

(12) United States Design Patent (10) Patent No.: US D1,100,520 S
(45) Date of Patent: * Nov. 4, 2025

(54) WORK LOUNGE

(71) Applicant: Kimball International, Inc., Jasper, IN (US)

(72) Inventors: Pamela D. Light, Los Angeles, CA (US); John C. Duffy, Carpinteria, CA (US)

(73) Assignee: Kimball International, Inc., Jasper, IN (US)

() Term: 15 Years

(21) Appl. No.: 30/004,687

(22) Filed: May 21, 2025

Related U.S. Application Data

(62) Division of application No. 29/891,259, filed on May 3, 2023.

(51) LOC (15) Cl. 06-01

(52) U.S. Cl. D6/334
USPC D6/334
